UNITED STATES PATENT OFFICE.

HENRY M. SUTTON, WALTER L. STEELE, AND EDWIN G. STEELE, OF DALLAS, TEXAS.

DRY ORE-CONCENTRATOR.

SPECIFICATION forming part of Letters Patent No. 747,265, dated December 15, 1903.

Application filed December 8, 1902. Serial No. 134,443. (No model.)

To all whom it may concern:

Be it known that we, HENRY M. SUTTON, WALTER L. STEELE, and EDWIN G. STEELE, citizens of the United States, residing at Dallas, in the county of Dallas, State of Texas, have invented certain new and useful Improvements in Dry Ore-Concentrators, of which the following is a specification, reference being had therein to the accompanying drawings.

This invention relates to a dry ore-concentrator, and particularly to a structure comprising a moving pervious belt, through which a pressure of air is passed for the purpose of performing a concentration upon the surface of the belt.

The invention has for an object to materially improve the means for introducing the air intermittently through the belt in its passage over the air-chambers and for collecting the results of the concentration.

A further object of the invention is to provide improved means for supporting and adjusting the table at different inclinations and driving the same when so adjusted.

Another object of the invention is to improve the structure of riffle and driving means therefor in order to secure the most efficient results of the operation of the machine.

Other and further objects and advantages of the invention will be hereinafter set forth, and the novel features thereof defined by the appended claims.

In the drawings, Figure 1 is a side elevation of the machine; Fig. 2, a vertical longitudinal section thereof; Fig. 3, a detail vertical cross-section showing the belt, riffle, and driving means therefor. Fig. 4 is a side view of the driving means for the belt-conveying rollers; Fig. 5, an end view of the same; Fig. 6, a detail perspective of the connection between the riffle and a link of the driving-chain; Fig. 7, a detail vertical section showing the adjusting means for the lower end of the table; Fig. 8, a detail longitudinal section through the belt and one of the riffles. Fig. 9 is a detail of a modified arrangement of the riffles upon the belt. Fig. 10 is a detail vertical section, upon an enlarged scale, through the clean-up chamber. Fig. 11 is a detail plan of the air-cut-off slats with the

reticulated supporting-surface broken away. Fig. 12 is a detail plan of the cone-pulleys and the belt-adjuster therefor, and Fig. 13 is an enlarged vertical section through the discharging-roller at the upper end of the table.

Like letters of reference refer to like parts in the several figures of the drawings.

The letter A designates a supporting-frame of any desired construction, preferably provided with an inclined upper surface A', upon which a working-table B is supported at its upper end by means of standards B', pivotally connected thereto, as shown at B², and at its lower end by means of an adjusting-standard B³, having a threaded upper end B⁴, adapted to receive an interiorly-threaded sprocket-wheel B⁵, upon which a bracket B⁶ from the table B rests. The sprockets at opposite sides of the table are connected by means of chains B⁷, so as to be adjusted simultaneously and to the same extent, while after the adjustment desired is reached the parts may be locked in their position by means of a nut B⁸, disposed upon the threaded end of the standard B³ above the bracket B⁶, as shown in Figs. 1 and 7. The working-table B, as shown in Fig. 2, has upon its upper surface a perforated support C, which is supported at suitable intervals by means of cross-slats C', spaced any desired distance apart at the lower end of the table to cut off the air to a portion of the belt lying above them. Beneath these slats a partition C² is disposed and provided with inwardly-opening valves of any desired construction—for instance, the flap-valves C³, as shown—thus comprising an air-chamber C⁴, in which the air will be under a continual pressure. Below the partition C² a bellows C⁵ is provided and pivoted at its lower end C⁶, the lower wall C⁷ of said bellows being provided with a series of inwardly-opening valves C⁸ and with a transverse partition C⁹, thus dividing the bellows into a lower chamber C¹⁰ and an upper clean-up chamber C¹¹. At the lower end of the table a dust-hopper D is formed and provided with a plate D' over its upper portion, so that the contents thereof shall not be displaced by the air-pressure, while an entrance-opening D² is formed at the lower end of the plate. Above this opening an

aperture D³ is formed in the partition C² to permit the passage of dust which may collect in the chamber C⁴ downward into the hopper, which is provided with any suitable form of removable side or door D⁴ for emptying the same when desired. It will be seen that the lower bellows in connection with the pressure-chamber C⁴ maintains a continual air-pressure upon the lower portion of the 10 table, which passes outward intermittently through the different parts of the traveling pervious belt E, lying in supporting contact with the perforated plate C. The pressure-chamber above the clean-up chamber C¹¹ is 15 provided with a spring-controlled relief-valve F⁵ at the upper end thereof, and the bellows is separated therefrom by a partition F and from the chamber C⁴ by a transverse partition F'. The apertured partition is supplied 20 with a series of inwardly-opening flap-valves F², while beneath the pervious belt and perforated plate a series of slats F³ are disposed and spaced from each other a distance equal to the width of the riffles E', carried 25 by the pervious belt E, so that as these riffles lie over the spaces the supply of air is cut off, and as they pass over the slats an intermittent blast is given to the concentrates carried upon the pervious belt. At this or 30 any other desired point a cleaning-brush F⁴ is pivotally mounted above the riffles and adapted to contact with the upper face thereof to remove any surplus material thereon. The pervious belt E after traveling over the 35 table passes over a roller G, having flaps G', of flexible material, such as rubber or leather, adapted to retain their general shape in use and extending longitudinally thereof, which engage the belt between the riffles and cause 40 the pervious cloth thereof to extend or project outward when passing over the roller, thus facilitating the deposit of the concentrates in the hopper G² provided therefor and supported by the frame at the upper end of the table. The pervious belt passes thence 45 downward beneath the table and over the guide-rollers G³, G⁴, and G⁵, if found desirable, while beneath this lower layer of the belt a dust pan or shelf G⁶ is provided to 50 catch all adhering particles which may fall from the belt and conduct them to a proper point of discharge.

The material to be operated upon is fed upon the pervious belt from the hopper H, supported in any suitable manner—for instance, by standards H', extending upward from the inclined face A' of the frame. The hopper is provided at its lower end with a discharge-spout H², beneath which a reciprocating pan H³ is mounted by means of rods H⁴, extending downward from the upper portion H¹⁰ of the hopper and pivotally connected to the pan at H⁵, and is adapted to be reciprocated from a driving eccentric H⁶, carried by a driving-shaft H⁷, suitably mounted upon one of the standards H', and provided with a driving-pulley H⁸, driven by the belt H⁹ from any

suitable source of power. This hopper is adapted to discharge the material at a point upon the table between the intermittent blast portions, so that the ore which travels downward in the initial action is subsequently brought by the belt over the upper intermittent blast.

For the purpose of driving the bellows and 75 endless pervious belt a driving-shaft I is mounted in the frame and supplied at one end with a driving-pulley I' and between its ends with a speed-regulating cone I², communicating with a similar oppositely-disposed cone I³ by means of a connecting-belt I⁴, which passes through a suitable belt-sifter I⁵, mounted upon the frame for the purpose of adjusting the belt to vary the speed of the apparatus and the consequent motion of the bellows, which is connected to the cone I³ by means of a rod I⁶, adjustably secured at I⁷ by a coupling disposed eccentrically to the shaft of the cone and pivoted to the bellows at the upper end I⁸. One end of the driving-shaft 90 I is also provided with a worm-wheel J, adapted to mesh with a gear J', carried upon a shaft J², supported in the framework of the apparatus and having at its opposite end a beveled gear J³, meshing with a corresponding gear J⁴ upon the lower end of the vertical shaft J⁵, which is supported in any desired manner—for instance, by means of a collar-bracket J⁶—from the frame of the machine. The upper end of this shaft has secured 95 thereto a worm-wheel J⁷, meshing with a gear J⁸, secured to the end of the roller G for the purpose of driving the same. Upon the end of this roller and also the guide-rollers G³, G⁴, and G⁵ sprocket-teeth are provided adapted 100 to engage with the chain-sections K, carried by the belt and connected to the riffles, thus providing a positive driving means for carrying the pervious belt in its predetermined path. The chain K is adapted to lie within 105 a recess K' at the sides of the table as the belt passes over the perforated face C.

The riffles, which may be formed of any desired material, are adapted to be secured to the pervious belt E in an improved manner by means of the metallic braces K², which extend beneath the belt and are provided with an angularly-disposed portion K³ to bring the outer end K⁴ into alignment with the chain-links K, which links are provided upon one side with a connecting-plate K⁵, adapted to be secured to the end K⁴ by a rivet K⁶, as shown in Figs. 3 and 6. The pervious belt E lies over this brace and above the belt, and below the brace are leather belts K⁷, disposed within the recess K' to fill the space at the edge of the recess, while between the riffles a leather filling K⁸ extends for a similar purpose, as shown by the detail in Fig. 8. Disposed above the metal brace K² is a riffle-block K⁹, preferably of wood, having an angular portion to hold the pervious belt in contact with one end of the brace K², thus preventing any movement of the riffle longi-

tudinally of the belt, while upon the upper surface of this block a metal strip K¹⁰ extends and is adapted to take the wear incident to the contact of the ore therewith, all of said parts being secured together by a bolt K¹¹, if so desired.

In the operation of the invention the ore is fed upon the endless moving pervious belt and carried thereby over the perforated plate 10 through which the air-pressure passes, and the lower portion of this belt is under an intermittent blast of one duration, while an intermittent blast of a different duration is provided at the upper part thereof by means 15 of the passage of the riffles over the slats of the table. It will be observed that the bellows has been divided by a flexible partition into an upper and lower chamber connecting with the respective air-chambers for effecting 20 the intermittent blasts. The perforated table over which the riffled pervious belt travels is provided with slats beneath the same, so that the lower portion of the table forms a separator and the upper portion a clean-up 25 chamber. The slats in the lower portion reduce the area of opening through which the air passes and cause the ore to be intermittently acted upon by the air when the portion of the belt between the riffles is over the space 30 between the slats. As the riffle carrying the ore travels upward over this portion of the table it passes from an active to an inactive portion and the upper part of the ore in the riffle is first acted upon, and thus allowing 35 the values in the ore or gravel being treated to settle to the cloth and to be caught in the riffles. In the clean-up chamber at the upper portion of the table the slats are spaced apart substantially the width of each riffle, and the 40 slats are of equal width. This causes the riffles carried by the belt to act as sliding valves, opening and closing openings below as they pass over the slats. As the riffles pass over the openings between the slats, gradually 45 closing the same, the air is concentrated on the ore carried by the belt, which forces the gangue or light particles over the riffle into the pocket below, and as the riffle leaves the open space the air is concentrated on this 50 gangue just forced over and blown farther down the table. This action is repeated as each riffle passes over the open space in the table. The revolving brush over this portion of the table is only used when the material 55 carries a quantity of fine compressible material which would ride on the top of the riffle and fall into the concentrates-hopper at the upper end of the table without being properly concentrated. The brushes thus 60 keep the top of the riffles clean, while the valves to the air-chamber beneath the slat prevent all back pressure of the air on the down-stroke of the bellows. The dust-hopper at the lower end of the table is arranged to receive 65 all dust that should pass through the pervious belt, and this dust works downward through the slot in the bottom, so that it is

forced into the hopper upon each stroke of the bellows. The dust-pan beneath the table is arranged to catch all particles of material adhering to the pervious cloth which fall off the belt as it travels beneath the table and may be caught in a receptacle at the foot of the pan. The roller at the upper end of the table over which the traveling belt 70 passes is provided with flexible flaps or projections, which cause the cloth between the riffles to project or extend as it passes over the roller, and the concentrates thus carried by the riffles slide upon the projection and 75 are thus prevented from striking the back of the riffle ahead, while the projection of the cloth increases the diameter of the roller at that point, which causes the concentrates to fall farther over into the hopper. The riffles are provided with a wooden strip secured between two metal faces—the riffle-support beneath the belt and the metal capping above the wood—which makes a very strong and 80 stiff riffle and one which when riveted to a belt-chain may be used to convey the belt in the most desirable manner. The leather belts secured at the edges of the pervious belt form a closure for the open end of the recess within which the belt-chain is disposed, and 85 thus prevent the collection of ore or dirt therein, which would be liable to interfere with the operation of the belt. The structure of driving means is adapted to permit a definite regulation of speed of both the bellows 90 and traveling apron relative to each other and also to allow an adjustment of the bellows' stroke in order to maintain the desired pressure within the chamber for the most effectual action, while the adjustment of the 95 lower end of the table permits the inclination thereof to be varied, so that the fall of particles by gravity can be regulated to any extent.

An important feature of this invention is 100 the graduated air-pressure in the clean-up chamber, which is controlled by the valve F⁵, before described, which may be of any desired character, although shown in detail in Fig. 10 as comprising a flap-valve F⁶, covering 105 an opening F⁷ from the clean-up chamber and normally held closed by the spring F⁸, the tension of which may be adjusted to any desired degree by means of an adjusting-screw F⁹, mounted in the bracket F¹⁰. It will 110 be seen that the maximum pressure is controlled by this valve, and the riffles opening and closing the air-outlets concentrate the blast on the remaining material carried by the belt until the gangue has been separated 115 from the values and by an adjustment of the spring tension the air-pressure for the blast may be determined, depending upon the character of ore operated upon. When the riffle passes over the open space, there is a 120 short rest which allows the values and other material to settle down between the riffles until they again reach an open space, when the air is concentrated on the ore, gradually 125 130

beginning at its upper edge, where it is thin-
nest and where the least values are, as each
agitation of the mass allows the values to
settle downward and toward the angle be-
tween the riffle and the belt.

In Fig. 9 a detail of a modified arrangement
of riffles upon the belt E is shown, which is
adapted for use upon fine dry ore and com-
prises alternate riffles E³ of greater height
than the intermediate riffles E⁴. This ar-
rangement reduces the amount of concen-
trates brought over by the belt nearly one-
half and provides double the number of rif-
fles for saving fine values, while the riffles
being close together the cloth is held perfectly
tight and true, so as to be prevented from
flapping or pitching at each stroke of the bel-
lows. It will be understood that the belt in
all forms of this invention travels continu-
ously, and the intermittent action of the air
upon the ore is secured by an arrangement
of slats beneath the belt and relative to the
width of the riffles.

It will be obvious that changes may be
made in the details of construction and con-
figuration of the several parts without de-
parting from the spirit of the invention as de-
fined by the appended claims.

Having described our invention and set
forth its merits, what we claim, and desire to
secure by Letters Patent, is—

1. In a dry ore-concentrator, a table, a mov-
ing pervious belt thereon, means for produc-
ing an air-pressure through said belt, riffles
upon said belt, and slats beneath the belt dis-
posed relative to the riffles and adapted to
cover the belt between adjacent riffles; sub-
stantially as specified.

2. In a dry ore-concentrator, a table, a mov-
ing pervious belt thereon, means for produc-
ing an air-pressure through said belt, riffles
upon said belt, slats beneath the belt spaced
relative to the width of said riffles, those slats
at the upper portion of the table being closer
together than those below the same; substan-
tially as specified.

3. In a dry ore-concentrator, a table, a mov-
ing pervious belt thereon, means for produc-
ing an air-pressure through said belt, riffles
upon said belt, slats beneath the belt spaced
relative to the width of said riffles, those slats
at the upper portion of the table being closer
together than those below the same, and a
hopper disposed above the table and inter-
mediate of the ends thereof; substantially as
specified.

4. In a dry ore-concentrator, a table, a mov-
ing pervious belt thereon, means for produc-
ing an air-pressure through said belt, riffles
upon said belt, slats beneath the belt disposed
relative to the riffles and adapted to cover the
belt between adjacent riffles, an air-chamber
beneath the belt, and means for regulating
the maximum pressure of air in said cham-
ber; substantially as specified.

5. In a dry ore-concentrator, an inclined
table, an endless pervious belt mounted there-

on and provided with riffles, means for con-
tinuously moving said belt, a series of slats
extending parallel to said riffles and adapted
to cover the belt between adjacent riffles, and
an air-chamber beneath said slats; substan-
tially as specified.

6. In a dry ore-concentrator, an inclined
table, an endless pervious belt mounted there-
on and provided with riffles, means for con-
tinuously moving said belt, a series of slats
extending parallel to said riffles and adapted
to cover the belt between adjacent riffles, a
valved partition to form an air-chamber be-
neath said slats, and a bellows beneath said
air-chamber for providing a pressure of air
therein; substantially as specified.

7. In a dry ore-concentrator, an inclined
table, an endless pervious belt mounted there-
on and provided with riffles, means for con-
tinuously moving said belt, a series of slats
extending parallel to said riffles and adapted
to cover the belt between adjacent riffles, a
valved partition to form an air-chamber be-
neath said slats, a bellows beneath said air-
chamber for providing a pressure of air there-
in, a transverse partition in said air-chamber
to comprise a clean-up chamber in the upper
end thereof, and a transverse partition in
said bellows to form an independent air-sup-
ply for the clean-up chamber; substantially
as specified.

8. In a dry ore-concentrator, an inclined
table, an endless pervious belt mounted there-
on and provided with riffles, means for con-
tinuously moving said belt, a series of slats
extending parallel to said riffles and beneath
the belt, an air-chamber beneath said slats,
a bellows beneath said air-chamber for pro-
viding a pressure of air therein, a transverse
partition in said air-chamber to comprise a
clean-up chamber in the upper end thereof,
a transverse partition in said bellows to form
an independent air-supply for the clean-up
chamber, a dust-hopper at the lower portion
of the table having an inlet thereto at its
lower portion; substantially as specified.

9. In a dry ore-concentrator, an inclined
table, an endless pervious belt mounted there-
on and provided with riffles, means for con-
tinuously moving said belt, a series of slats
extending parallel to said riffles and beneath
the belt, an air-chamber beneath said slats,
a bellows beneath said air-chamber for pro-
viding a pressure of air therein, a transverse
partition in said air-chamber to comprise a
clean-up chamber in the upper end thereof,
a transverse partition in said bellows to form
an independent air-supply for the clean-up
chamber, a dust-hopper at the lower portion
of the table having an inlet thereto at its
lower portion, means for regulating the maxi-
mum air-pressure in said clean-up chamber,
and a concentrates-hopper at the upper end
of said table; substantially as specified.

10. In a dry ore-concentrator, an inclined
table, an endless pervious belt mounted there-
on and provided with riffles, means for con-

tinuously moving said belt, a series of slats extending parallel to said riffles and beneath the belt, an air-chamber beneath said slats, a bellows beneath said air-chamber for pro-

viding a pressure of air therein, a transverse partition in said air-chamber to comprise a clean-up chamber in the upper end thereof, a transverse partition in said bellows to form an independent air-supply for the clean-up chamber, a dust-hopper at the lower portion of the table having an inlet thereto at its lower portion, means for regulating the maximum air-pressure in said clean-up chamber, a concentrates-hopper at the upper end of said table, and a bearing-roller for said belt at the upper end of the table having flexible blades thereon to bear upon the belt between the riffles; substantially as specified.

11. In a dry ore-concentrator, a table having at its lower portion a series of transverse slats spaced apart and at its upper portion similar slats spaced closer together than the lower slats, a moving pervious belt, riffles upon said belt of equal width to the spaces between the upper slats of the table, and an independent air-chamber beneath the upper and lower sections of slats; substantially as specified.

12. In a dry ore-concentrator, a table having at its lower portion a series of transverse slats spaced apart and at its upper portion similar slats spaced closer together than the lower slats, a moving pervious belt, riffles upon said belt of equal width to the spaces between the upper slats of the table, a partition beneath said slats having inwardly-opening valves, a transverse partition between the slats and valved partition to form independent air-chambers beneath the slats, and a bellows secured to said valved partition and provided with a transverse partition therein to form independent air-feeding means for each chamber; substantially as specified.

13. In a dry ore-concentrator, a table having at its lower portion a series of transverse slats spaced apart and at its upper portion similar slats spaced closer together than the lower slats, a moving pervious belt, riffles upon said belt of equal width to the spaces between the upper slats of the table, a partition beneath said slats having inwardly-opening valves, a transverse partition between the slats and valved partition to form independent air-chambers beneath the slats, a bellows secured to said valved partition and provided with a transverse partition therein to form independent air-feeding means for each chamber, a feed-hopper above said belt disposed to discharge thereon between the sections of slats, and means for simultaneously driving said belt and bellows; substantially as specified.

14. In a dry ore-concentrator, a table having at its lower portion a series of transverse slats spaced apart and at its upper portion similar slats spaced closer together than the

lower slats, a moving pervious belt, riffles upon said belt of equal width to the spaces between the upper slats of the table, a partition beneath said slats having inwardly-opening valves, a transverse partition between the slats and valved partition to form independent air-chambers beneath the slats, a bellows secured to said valved partition and provided with a transverse partition therein to form independent air-feeding means for each chamber, a feed-hopper above said belt disposed to discharge thereon between the sections of slats, means for simultaneously driving said belt and bellows, a cleaning-brush disposed above said slats, a concentrates-hopper at one end of the table, and a bearing-roller for the belt above said hopper having flexible blades to discharge the concentrates from the belt; substantially as specified.

15. In a dry ore-concentrator, a table having at its lower portion a series of transverse slats spaced apart and at its upper portion similar slats spaced closer together than the lower slats, a moving pervious belt, riffles upon said belt of equal width to the spaces between the upper slats of the table, a partition between said slats having inwardly-opening valves, a transverse partition between the slats and valved partition to form independent air-chambers beneath the slats, a bellows secured to said valved partition and provided with a transverse partition therein to form independent air-feeding means for each chamber, a feed-hopper above said belt disposed to discharge thereon between the sections of slats, means for simultaneously driving said belt and bellows, a cleaning-brush disposed above said slats, a concentrates-hopper at one end of the table, a bearing-roller for the belt above said hopper having flexible blades to discharge the concentrates from the belt, a pan extending beneath the table and belt for receiving material carried by the belt past the concentrates-hopper; substantially as specified.

16. In a dry ore-concentrator, an inclined table, a riffled belt mounted for movement thereover, slats beneath said belt disposed relatively to riffles thereon, independent air-chambers beneath said slats and means for maintaining a different pressure of air in each of said chambers to produce a separating action at the lower portion of the table and a cleaning-up action at the upper portion thereof; substantially as specified.

17. In a dry ore-concentrator, a pervious belt, a riffle disposed thereon having a depending lip upon its under face, a brace for said riffle extending beneath the belt and engaging said lip, and a carrier-chain connected to the end of said brace; substantially as specified.

18. In a dry ore-concentrator, a pervious belt, a riffle disposed thereon, a brace for said riffle extending beneath the belt, a carrier-chain connected to the end of said brace, a

side wall provided with a recess to receive said chain, and a filling material carried by the belt between the adjacent riffles thereof, and a flexible belt above said riffles and filling 5 material to close the open end of said recess; substantially as specified.

19. In a dry ore-concentrator, a pervious belt, a riffle disposed thereon having a depending lip upon its under face, a brace for 10 said riffle extending beneath the belt and engaging said lip, a carrier-chain connected to the end of said brace, a side wall provided with a recess to receive said chain, a filling material carried by the belt between the adjacent 15 riffles thereof, a flexible belt above said riffles and filling material to close the open end of said recess, an angular portion to said brace to dispose the ends thereof in a parallel plane above the body, and a wear- 20 plate secured to the upper surface of said riffle by means extending through the riffle and plate; substantially as specified.

20. In a dry ore-concentrator, a table, an endless belt thereon, a bellows beneath said 25 table, a driving-shaft provided with a cone-pulley, a counter-shaft provided with a corresponding cone-pulley, a driving-belt between said cone-pulleys, means for shifting said belt, and a connecting-rod extending 30 from the bellows and connected by a slideable sleeve to the cone-pulley upon said counter-shaft eccentrically of its axis; substantially as specified.

21. In a dry ore-concentrator, a table, an 35 endless belt thereon, a bellows beneath said table, a driving-shaft provided with a cone-pulley, a counter-shaft provided with a corresponding cone-pulley, a driving-belt between said pulleys, means for shifting said 40 belt, a connecting-rod extending from the bellows, a sleeve-coupling to receive said rod carried by the cone-pulley upon said counter-shaft eccentrically of its axis, a worm upon the end of said driving-shaft, and a gearing 45 extending therefrom to continuously drive said belt; substantially as specified.

22. In a dry ore-concentrator, a table, an endless belt thereon, a bellows beneath said table, a driving-shaft provided with a cone-pulley, a counter-shaft provided with a corresponding pulley, a connecting-rod extending 50 from the bellows and adjustably connected to the pulley upon said counter-shaft eccentrically of its axis, a worm upon the end 55 of said driving-shaft, a gearing extending therefrom to continuously drive said belt, and means for shifting the belt between the cone-pulleys to vary the speed of the bellows independently of the driving speed of the 60 belt; substantially as specified.

23. In a dry ore-concentrator, a frame having an inclined upper portion, an inclined table supported thereon, an endless pervious belt provided with riffles, means for continuously 65 driving said belt, a slatted top to said table, independent air-chambers beneath the upper and lower portions of said top, an adjustable

relief-valve for determining the air-pressure in the upper chamber, and a hopper adapted to feed ore upon said table between the ends thereof; substantially as specified.

24. In a dry ore-concentrator, a frame having an inclined upper portion, an inclined table supported thereon, an endless pervious belt provided with riffles, means for continuously driving said belt, a slatted top to said table, independent air-chambers beneath the upper and lower portions of said top, an adjustable relief-valve for determining the air-pressure in the upper chamber, a hopper adapted to feed ore upon said table between the ends thereof, a concentrates-hopper at the upper end of the table, a driving-roller for the belt having flexible blades to discharge the material between the riffles thereof, a pan extending beneath the lower layer of the belt, and a bellows having independent compartments beneath each of the air-chambers; substantially as specified.

25. In a dry ore-concentrator, a frame having an inclined upper portion, an inclined table supported thereon, an endless pervious belt provided with riffles, means for continuously driving said belt, a slatted top to said table, independent air-chambers beneath the upper and lower portions of said top, an adjustable relief-valve for determining the air-pressure in the upper chamber, a hopper adapted to feed ore upon said table between the ends thereof, a concentrates-hopper at the upper end of the table, a driving-roller for the belt having flexible blades to discharge the material between the riffles thereof, a pan extending beneath the lower layer of the belt, a bellows having independent compartments beneath each of the air-chambers, a dust-hopper at the lower portion of the table communicating with the lower air-chamber and with the bellows, means for adjusting the lower end of the table, and driving means for operating said belt and bellows at different speeds; substantially as specified.

26. In a dry ore-concentrator, a frame having an inclined upper portion, an inclined table supported thereon, an endless pervious belt provided with riffles, means for continuously driving said belt, a slatted top to said table, independent air-chambers beneath the upper and lower portions of said top, an adjustable relief-valve for determining the air-pressure in the upper chamber, a hopper adapted to feed ore upon said table between the ends thereof, a concentrates-hopper at the upper end of the table, a driving-roller for the belt having flexible blades to discharge the material between the riffles thereof, a pan extending beneath the lower layer of the belt, a bellows having independent compartments beneath each of the air-chambers, a dust-hopper at the lower portion of the table communicating with the lower air-chamber and with the bellows, means for adjusting the lower end of the table, driving means for operating said belt and bellows at different speeds; substantially as specified.

- speeds, a cleaning-brush disposed above the upper face of said belt, a carrier-chain secured to supporting-bars beneath the belt, and bearing-rollers meshing with said chain for conveying the belt throughout its length; substantially as specified. 5
27. In a dry ore-concentrator, a frame having an inclined upper portion, an inclined table supported thereon, an endless pervious belt provided with riffles, means for continuously driving said belt, a slatted top to said table, independent air-chambers beneath the upper and lower portions of said top, an adjustable relief-valve for determining the air-pressure in the upper chamber, a hopper adapted to feed ore upon said table between the ends thereof, a concentrates-hopper at the upper end of the table, a driving-roller for the belt having flexible blades to discharge the material between the riffles thereof, a pan extending beneath the lower layer of the belt, a bellows having independent compartments beneath each of the air-chambers, a dust-hopper at the lower portion of the table communicating with the lower air-chamber and with the bellows, means for adjusting the lower end of the table, driving means for operating said belt and bellows at different speeds, a cleaning-brush disposed above the upper surface of said belt, a carrier-chain secured to supporting-bars beneath the belt, bearing-rollers meshing with said chain for conveying the belt throughout its length, a reticulated surface above said slats in contact with which the belt travels, and a cover-plate for said dust-hopper to prevent air-pressure acting therein; substantially as specified. 35
28. In a dry ore-concentrator, a table, means for passing air therethrough, a pervious belt upon said table provided with riffles, a bearing-roller for said belt having blades adapted to discharge material from the belt by projecting the portion thereof between the riffles thereon, means for rotating said roller, and a concentrates-hopper beneath said roller; substantially as specified. 40
29. In a dry ore-concentrator, a table, a pervious belt provided with riffles and adapted to travel over said table, an air-chamber beneath said table, and means for passing an intermittent air-blast of one duration through portions of the belt at the lower portion of the table and of a different duration through portions of the belt at the upper portion thereof; substantially as specified. 45
30. In a dry ore-concentrator, a table, a clean-up chamber at the upper portion thereof having a slatted surface, a belt adapted to travel over said chamber and provided with riffles to close the spaces between the slats, a governing-valve for determining the air-pressure of said chamber, a spring bearing upon said valve, and an adjusting-screw to vary the pressure of said spring upon said valve; substantially as specified. 50
